GAME DEVICE

Warner Stauffacher, Minneapolis, Minn.

Application April 3, 1943, Serial No. 481,662

9 Claims. (Cl. 273—110)

This invention relates to game devices.

It is a general object of the invention to provide a mechanical game device made up of two or more relatively movable bases or supports adapted to have movable game pieces resting thereon and also to provide means for deflecting the game pieces from one of the base elements or supports to the other as relative movement takes place between the base elements.

More specifically it is an object of the invention to provide a pair or more of rotary game piece supports with movable game pieces thereon and game piece transfer means which is swingable over the supports adjacent their edges to intercept and deflect the game pieces from one rotary support to the other. The game pieces are distinctively shaped or identified so that the players can separately identify them with the object of transferring only certain of the game pieces from one rotary support to the other to segregate different classes of game pieces.

These and other objects and advantages of the invention will more fully appear from the following description made in connection with the accompanying drawings, wherein like reference characters refer to the same parts throughout the views, and, in which:

Fig. 1 is a plan view of one form of the invention;

Fig. 2 is a side elevation thereof; and

Fig. 3 is a plan view of a modified form of the invention.

In Fig. 1 there is shown a main frame including vertical side pieces 4 and 5 connected by ends 6 and 7. A shaft 8 is journalled between the frame and pieces 6 and 7 and is shown to extend throughout the lengths of the frame side members 4 and 5. A crank 9 is provided on one end of the shaft 8 so that it can be rotated. The frame is provided with a pair of cross members 10 and 11 which extend laterally from the frame side members 4 and 5 and are journalled between the shafts 12 and 13 which extend through and a considerable distance beyond the cross member 11. The shaft 8 which is parallel to the laterally disposed shafts 12 and 13 is provided with a pulley 14, and the shafts 12 and 13 are provided with pulleys 15 and 16. Suitable belts 17 and 18 connect the pulley 14 with pulleys 15 and 16 respectively. The opposite ends of shafts 12 and 13 are provided with idler pulleys 19 and 20. Extending upwardly from opposite ends of the cross member 11 are pivot pins 21 upon which are fitted for free rotation discs 22 and 23.

The pulleys 15 and 16 on the shafts 12 and 13 are provided with friction surfaces 24 which are adapted to engage the undersides of the rotary discs 22 and 23 so that when the crank 9 and shafts 8 are rotated pulleys 14, 15 and 16 will also be rotated, and their drive belts 17 and 18 are so arranged that the rotation of these three pulleys is in the same direction. The idler pulleys 19 and 20 merely support the discs 22 and 23 at points opposite to the pulleys 15 and 16.

The frame side members 4 and 5 have a cross member 25 positioned between them adjacent the ends of said side members opposite from the end where the hand crank 9 is located. The cross member 25 is provided with a pivot pin 26 upon which is rotatably mounted a third disc 27. A pulley 28 having a friction surface similar to the pulleys 15 and 16 is fixed on the shaft 8 beneath the disc 27, and the idler pulley 29 on shaft 8 assists in supporting the opposite side of the disc 27. Because of the position of the friction roller or pulley 28 relative to its pivot 26 the disc 27 will be rotated in a direction opposite to that of the discs 22 and 23. The three discs 22, 23 and 27, while positioned closely adjacent each other, are spaced slightly apart so their edges do not contact, and as shown in Fig. 2 the three discs are all at the same level.

A diagonally disposed cross member 30 extends from the frame side member 5 through the side member 4 and some distance outwardly therefrom. Adjacent the ends of the diagonal cross member 30 are vertically disposed shafts 31 and 32. These shafts extend above and below the cross member 30 as shown in Fig. 2, and on the lower ends of said shafts are connected cranks 33 and 34. The outer ends of said cranks are connected by a tie rod 34a. The shaft 31 has a second crank 35 mounted thereon, and it is connected to an actuating rod 36 which extends rearwardly to the end of the side frame member 4 adjacent the hand crank 9 where said operating rod is connected to a pivoted hand lever 37 which is suitably secured to the side frame member 4.

The upper ends of the vertically disposed shafts 31 and 32 have transfer devices or gates 38 and 39 mounted thereon. As best shown in Fig. 1, when the hand lever 37 is shifted it will swing the transfer gates 38 and 39 from their full line positions to their dotted line positions. In the full line positions of the gate they lie over the disc 27 and in their dotted line positions they lie over the discs 22 and 23.

Positioned on the discs 22, 23 and 27 are mov-

able game pieces 40 and 41. The game pieces 40 are marked with plain circles, whereas the game pieces 41 are identified by colored circles.

In operation the game pieces may be placed upon the disc 27 which I term a transfer disc or support, and said game pieces are positioned around the edge of said disc 27. To illustrate one method of playing the game the player may begin turning the hand crank 9 to rotate the main shaft 8 and the three discs 22, 23 and 27. As indicated by arrows, discs 22, 23 rotate in the counterclockwise direction when the hand crank 9 is turned in a clockwise direction, and the transfer disc 27 will be rotated in a clockwise direction. As the disc 27 rotates the game pieces will successively approach either the transfer gate 39 or gate 38. If it is desired to corral or collect all the plain circular game pieces 40 on the disc 23, the gates should be operated so that gate 39 will intercept and deflect the plain circled game pieces 40 from the disc 27 to said disc 23; and the gates might similarly be operated to transfer the colored game pieces 41 from the transfer disc 27 to the disc 22. Of course, any suitable arrangement of game pieces can be devised and the transfer from one disc to the other can be varied at will. Pieces can be transferred from disc 22 to the transfer disc 27 and then to disc 23 and vice versa.

Another embodiment of the invention is shown in Fig. 3 wherein there is provided a frame composed of side members 42 and 43 connected by end members 44 and 45. Intermediate the ends of the side members 42 and 43 are cross members 46, 47, 48, 49 and 50. The intermediate cross members 46, 48 and 50 are provided with vertically disposed pivot pins 51 on which are rotatably positioned discs 52, 53 and 54. A shaft 55 extends between the frame end members 44 and 45 and is provided with a hand crank 56. Mounted on shaft 55 for rotation therewith are frictional rollers or pulleys 57 and idler rollers 58. It should be noted that the frictional rollers 57 beneath the discs 52 and 54 are disposed oppositely to the friction roller 57 beneath the disc 53 so that when the crank 56 and shaft 55 are rotated the discs 52 and 54 will turn in the same direction and oppositely to the disc 53. Gates 59 on vertical shafts 60 are disposed at opposite sides of the center disc 53 and adjacent the end discs 52 and 54. Each shaft 60 upon which the gates 59 are mounted has a crank lever 61 thereon which is connected by a link 62 to a pivoted hand lever 63 similar to hand lever 37 in Figs. 1 and 2. In this embodiment of the invention the gates 59 are independently actuated by the hand levers 63 at opposite ends of the main frame of the device. Thus a player can stand at each end of the game apparatus and independently attempt to divert his or his opponent's game pieces from the center disc 53.

While the device may be employed as a game in any desired manner there is one method of manipulating it, particularly with reference to the embodiment shown in Figs. 1 and 2. The game pieces 40 and 41 are differently marked to differentiate between them but, for example, they might be in the form of different species of animals. The game pieces would first be placed upon the disc 27, for example, and the object would be to transfer game pieces of one identity to the disc 22 and those of another identity to the disc 23. In the embodiment of Figs. 1 and 2 the gates 38 and 39 operate together, and while

the player might be diverting a desired game piece from the transfer disc 27 to one of the other discs such as the disc 22 he might also intercept and transfer a game piece to the disc 23 because of the simultaneous operation of the gate 39.

It should be noted that the friction pulley 28 at the outer end of the shaft 8, which is the pulley contacting and rotating the disc 27, is positioned a different distance from the periphery of its disc than the pulleys 15 and 16 which drive discs 22 and 23. This causes the disc 27 to rotate at a different speed from discs 22 and 23. In the event the game pieces are so arranged on disc 27 that they cannot be conveniently transferred because of their spaced arrangement the crank 9 can be rotated until the relationship of the game pieces on the disc 27 and those on discs 22 and 23 have been changed because it sometimes happens that a game piece might be shifted from one disc to the other accidentally while the player is attempting to transfer another game piece.

It should also be noted that the transfer disc 21 of Figs. 1 and 2 and the transfer disc 53 in Fig. 3 are of larger diameter than the complementary discs adjacent to them. This also has an effect in varying the relative speeds of the discs. Of course, it should be understood that any suitable means for creating a different relative speed of rotation of the discs could be utilized.

From the foregoing it will be seen that I have provided a simply constructed and easily operated mechanical game apparatus which involves the transfer of movable game pieces mechanically from one to another of relatively movable game piece supports or discs by means of deflecting transfer devices or gates which can be actuated at will to pick out and transfer differently designated game pieces from one disc to another. The different methods of play can, of course, be varied considerably. In the embodiment shown in Figs. 1 and 2 end gates or transfer devices are operated together, whereas in the embodiment of Fig. 3 the gates are independently operated, and that form of the invention shown in Fig. 3 is considerably simpler in construction than that shown in the first embodiment.

While I have shown sets of three rotatable discs or supports for the game pieces it is, of course, to be understood that more or less than three can be used, and that various changes may be made in the form, arrangement, details, and proportions of the various parts without departing from the scope of my invention.

What is claimed is:

1. In a game device, a pair of relatively movable base elements having edge portions adjacent each other, a plurality of game pieces adapted to rest upon said base elements, and a game piece transfer device movably mounted adjacent said base elements and movable over said elements to deflect game pieces from one base element to the other.
2. In a game device: a pair of rotary base elements having edge portions adjacent each other, a plurality of game pieces adapted to rest upon said base elements, and a game piece transfer device movably mounted adjacent said base elements and movable over said elements to deflect game pieces from one base element to the other.
3. In a game device, a pair of rotary base elements having edge portions adjacent each other,

said base elements having substantially flat peripheral surfaces, a plurality of game pieces adapted to rest upon said base elements on their flat peripheral surfaces, and a game piece transfer device movably mounted adjacent said base elements and movable over said elements to deflect game pieces from one base element to the other.

4. The structure in claim 3, and said rotary base elements being movable in opposite directions.

5. In a game device, a pair of rotary base elements, an intermediate rotary transfer element adjacent edge portions of said pair of rotary base elements, and game piece transfer devices movably mounted adjacent said base elements and said transfer element and movable over said base elements and said transfer element to deflect game pieces from said base elements to said transfer element and from said transfer element to said base elements.

6. In a game device, a pair of rotary base elements, a rotary transfer element having portions thereof adjacent edge portions of said base elements, the axis of rotation of said base elements and transfer element forming the corners of a triangle, means for rotating said base elements in the same direction, means for rotating said transfer element in an opposite direction to said base elements, and game piece transfer means movably mounted adjacent said base ele-

ments and transfer element and swingable over said elements to deflect game pieces from said base elements to said transfer element and from said transfer element to said base elements.

7. The structure in claim 6, and said transfer means including a pair of transfer devices one for each base element, and means for simultaneously actuating said transfer device.

8. In a game device, a pair of spaced rotary base elements, a rotary transfer element between said base elements and having its edge adjacent the edges of said base elements, the axes of said transfer element and said base elements being in alignment, means for rotating said base elements in the same direction, means for rotating said transfer element in a direction opposite to that of said base elements, a plurality of game pieces adapted to rest upon said base elements and said transfer element, and game piece transfer means located between said transfer element and said base elements, said transfer means being mounted for movement over said base elements and said transfer element to deflect said game pieces from said base elements to said transfer element and from said transfer element to said base elements.

9. The structure in claim 8 and means for independently actuating the transfer means for each base element.

WARNER STAUFFACHER.
